UNITED STATES PATENT OFFICE.

EMMETT C. GRANT, OF FARMER VILLAGE, NEW YORK.

BUCKLE-PLATE.

SPECIFICATION forming part of Letters Patent No. 355,763, dated January 11, 1887.

Application filed April 30, 1886. Serial No. 200,692. (No model.)

To all whom it may concern:

Be it known that I, EMMETT C. GRANT, a citizen of the United States, residing at Farmer Village, in the county of Seneca and State of New York, have invented certain new and useful Improvements in Attaching Buckles, of which the following is a specification, reference being had therein to the accompanying drawings.

10 My invention relates to certain improvements in the manner of attaching buckles and loops to harness-straps, and it is designed to produce a simple and inexpensive device for effectively securing the buckle to the strap, and which at the same time will form a fastening and bearing-plate for one or more strap-retaining loops or keepers, as will be more fully hereinafter described, and particularly pointed out in the claim.

20 The invention consists of a metallic plate bent transversely about midway its length, and provided with two or more rivet-holes for the passage of rivets when securing it to the strap. This metallic plate is approximately the same width as the strap to which it is attached, and is secured to the under side of the same, so that a portion of it will overlap and protect the folded end of the strap after it is passed around the tongue-bar of the buckle.

25 30 The invention is fully illustrated in the accompanying drawings, in which—

Figure 1 represents a view of the reverse side of a strap with my device applied thereto, and Fig. 2 a longitudinal sectional view of the same.

35 In the drawings, A designates a strap, to which is attached the buckle B. A metallic plate, C, is bent slightly at a and provided

with two or more rivet-holes, by means of which and suitable rivets it is attached to the under side of the strap. A portion of this plate C overlaps and protects the folded end of the strap in such a manner as to securely fasten the buckle thereto. A rivet passes through the two thicknesses of the strap and the plate and is there clinched in the usual manner.

In a recess between the folded end of the strap and the bent portion of the metallic plate C strap-retaining loops D are secured. This space or recess is of sufficient size to allow each of the loops an independent and free movement.

It is manifest that my device will protect the folded end of the strap and attach the retaining-loops securely to the same, and at the same time will provide a durable fastening for the buckle.

Having thus fully described my invention, what I claim, and desire to secure by Letters Patent, is—

The combination, with a strap and buckle, of a metallic plate bent transversely about midway its length, as shown, and provided with rivet-holes near each end, by means of which and rivets it is secured to the strap so that a portion of its length will overlap and protect the folded end of the same and securely attach the buckle thereto, substantially as shown.

In testimony whereof I affix my signature in presence of two witnesses.

EMMETT C. GRANT.
